UNITED STATES PATENT OFFICE.

GEORGE H. BISHOP, OF ARCHBALD, PENNSYLVANIA.

SHINGLE.

Application filed January 15, 1926. Serial No. 81,492.

The present invention relates to shingles used in building construction, and has for its prime object to provide a shingle which may be laid by an unskilled person without the necessity of marking the roof or the place where the shingles are to be laid, or without the necessity of using specially constructed measuring apparatus.

Another important object of the invention is to provide a shingle of this nature which is curved longitudinally so that its edges will bear snugly against the surface on which the shingle is located.

Another important object of the invention is to provide a shingle of this nature having reinforced longitudinal side edges which prevent buckling and curling of the shingles and provide means for the reception of nails or like fastening elements.

Another very important object of the invention is to provide reinforcing edges of shingles of this nature which are provided with spacing enlargements so that the shingles will be held in proper spaced relation to each other to allow for the desirable circulation, expansion, and contraction.

A still further very important object of the invention, is to provide shingles of this nature having simple constructions, and which are inexpensive to manufacture, strong, durable, easy to lay, and otherwise well adapted to the purpose for which they are designed.

With the above and numerous other objects in view as will appear as the description proceeds, the invention resides in certain novel features of construction, and in the combination and arrangement of parts as will be hereinafter more fully described and claimed.

In the drawing:

Figure 1 is a plan view of a plurality of the shingles in proper arrangement,

Fig. 2 is a bottom plan view of one of the shingles,

Fig. 3 is a longitudinal section through one of the shingles, substantially taken on the line 3-3 of Fig. 2, and

Fig. 4 is an enlarged detail transverse section taken substantially on the line 4-4 of Fig. 1, and

Fig. 5 is a detail perspective view of one of the reinforcing edges.

Referring to the drawing in detail, I shall describe one shingle first as the arrangement of the shingles is more or less

conventional, as will appear as the description proceeds. Each shingle includes a body 5 formed of any suitable material, preferably using the composition of material now in common use. In the present instance, I have shown this body rectangular in formation, but do not wish to be limited to this particular formation. On the longitudinal edges of the body 5, there are disposed reinforcing elements, indicated generally by the letters A. Each reinforcing element is preferably formed from sheet metal substantially U-shaped in transverse cross section, to form a channel for receiving the edges of the body 5.

The closed edge of each element A, is provided intermediate its ends with an enlargement or spacing extension 6. The top side 7 of each element is provided with a plurality of apertures 8 for receiving fastening elements such as nails. The bottom side 9 of each element A has struck therefrom, a plurality of teeth 10, which are bent inwardly toward the top side 7 and are embedded into the material of the body 5, thereby holding the element A securely on the body. The body 5 and the element A are curved longitudinally as clearly shown in Fig. 3, so that when the shingle is laid on the roof with the convex surface uppermost, the ends thereof will be forced into snug engagement with the surface on which the shingle is being placed, when the fastening elements are driven thru the apertures 8, through the body 5, and through the bottom sides 9 for flattening out the shingle.

In Fig. 1 I have clearly shown the arrangement of the improved shingle. This arrangement is identical with the approved arrangement now well known in the art. The adjacent shingles are held in the desired spaced relation by means of the spacing extensions 6, thereby doing away with the necessity of any measurements or lay out markings on the roof or other surface. The bottom edges of the shingles are disposed at the juncture of the lower ends of the spacing extensions 6 of the bottom layer.

From the above description it will be seen that I have produced a highly novel shingle which may be laid by unskilled labor and by skilled labor without the necessity of any particular instruments or markings on the surface to be covered. The shingles are thoroughly reinforced and are capable of being easily assembled in the

proper relation on the surface to be covered.

The present embodiment of the invention has been disclosed in detail since in actual practice it attains all the features of advantage enumerated as desirable in the statement of the invention and the above description. It will be apparent, however, that numerous changes in the details of construction, and in the combination and arrangement of parts may be resorted to without departing from the spirit and scope of the invention as hereinafter claimed or sacrificing any of its advantages.

Having thus described my invention, what I claim as new is:

1. A shingle of the class described including a body, a pair of reinforcing elements on the side edges of the body, each reinforcing element being substantially U-shaped in formation to provide an upper side and a lower side, said upper side being

provided with a plurality of apertures, said lower side having portions struck upwardly therefrom to be embedded in the body, said body and said reinforcing elements being curved longitudinally.

2. A shingle of the class described including a body, a pair of reinforcing elements on the side edges of the body, each reinforcing element being substantially U-shaped in formation to provide an upper side and a lower side, said upper side being provided with a plurality of apertures, said lower side having portions struck upwardly therefrom to be embedded in the body, said body and said reinforcing elements being curved longitudinally, laterally disposed extensions on the reinforcing elements.

In testimony whereof I affix my signature.

GEORGE H. BISHOP.
